UNITED STATES PATENT OFFICE.

DANIEL B. HISER, OF SPRINGFIELD, OHIO.

COFFIN.

SPECIFICATION forming part of Letters Patent No. 326,559, dated September 22, 1885.

Application filed March 23, 1885. (No model.)

To all whom it may concern:

Be it known that I, DANIEL B. HISER, of the city of Springfield, county of Clark, and State of Ohio, have invented certain new and useful Improvements in Burial-Caskets, of which the following is a specification.

This invention relates to metallic caskets, cases, &c., the object of the invention being to provide a metallic casket that will be light, durable, easy to cast and set up, it being virtually an improvement upon the invention described and claimed in Patent No. 288,804, dated November 20, 1883, granted to me.

My invention consists, primarily, in the special construction of the sides, ends, cover, and caps, and the manner in which they are connected, the devices for attaching the sides, ends, and bottom together, the devices for securing the sides and cover together, and the manner in which the face-glasses are secured to the cover, all substantially as hereinafter described.

Figure 1 represents in central longitudinal section a metallic burial-casket constructed in accordance with my invention; Fig. 2, a cross-section on dotted line x x , Fig. 1, of the same; Fig. 3, an enlarged sectional detail of one side of the casket, taken on line y y , Fig. 1, the said Fig. 3 showing the device for locking the side and top of the casket together; Fig. 4, an enlarged sectional view of a portion of the cover as shown in Fig. 2; Fig. 5, details of the locking-lever for securing the top and sides of the casket together; Fig. 6, details of the fastening-plate for attaching the ends to the sides of the casket; Fig. 7, details of the plate for attaching the cover, sides, and ends of the casket together.

The casket consists of the metallic sides A, the two rounded ends B, bottom C, cover or top D, caps E, and the cap-covers E'.

The sides A of the casket, as well as their ends B, are cast with a double flanged rim, a, at their upper ends, and an internally-projecting flange, b, at their lower ends. To the flange b of the sides and ends is bolted the bottom plate, C, which bottom may be, if desired, of sheet metal. By casting the sides and ends each with a T-shaped upper end, as shown at a, and an L-shaped lower end, as shown at b, the upper end forms a wide bearing for the cover D to rest upon, and the lower

end forms, substantially, a portion of the bottom of the casket and a suitable flange to bolt the bottom to.

The sides and ends of the casket are secured together upon the inside of the casket by means of angled fastening-plates G H, having screw-holes, the ones G being bolted to the flange b of the sides and ends at the joint of said sides and ends, and having a portion which bears against the upright portion of said sides and ends, and the ones H being secured to the internally-projecting flanges a of the sides and ends by means of bolts, and having a portion to bear against the upright portion of said sides and ends at their joining-point.

The cover D is secured to the sides A and ends B by means of adjustable clips I, pivoted to the under side of the externally-projecting flanges of the sides and ends, as shown in Fig. 3, the said clip I having an open jaw-like end, I', which, when the clip is swung around in a line with the length of the casket, grasps the outside lower edge of the cover and the outside flange of the sides or ends, which firmly secures them together. By securing the cover to the body of the casket by adjustable clips, as described, the cover may be put on and fastened or removed with much less trouble and in less time than were it necessary to screw the cover to the sides and ends, as heretofore.

The cover D has face-glass depressions on its upper face, which depressions have a face-glass opening, d', the sides of the depressions being "stepped" or having two shoulders, d² d³, the shoulder d² being provided with a flexible gasket, d⁴, upon which rests the face-glass e, said face-glass being secured in place by means of a frame, e', bolted to the shoulder d³, as shown in Fig. 4, which frame e' has a flexible gasket, e², secured to its under side, which bears against the upper side of the face-glass.

It will be noticed by reference to Fig. 4 that the face-glass e rests upon the shoulder d² below the level of the face of the cover D, and that the frame e', which holds said glass in place, is about on a level with the face of the cover. This is desirable, as it gives a better finish to the cover, and said glass is less liable to be broken in shipping, &c.

The cover will be constructed of cast metal,

and to secure satisfactory results in casting, the sides or periphery of the cover will be formed with a curved lower or base portion, f , an instep, f' , a straight vertical or inclined central portion, f^2 , an instep, f^3 , and a beaded upper edge, f^4 , which configuration gives a handsome finish or symmetricalness to the said cover.

Secured to the cover D by means of screws 10 (not shown) are metallic protecting-caps E, the sides of which are preferably ogee-shaped, the said caps being open at the top, and provided with central covers, E', and, in consequence of the face-glass being below the level 15 of the cover D, they are made low, and are placed directly over the face-glasses to protect them.

The inside of the casket will be provided with wooden strips to fasten the drapery to, 20 as in caskets of ordinary construction.

I claim—

1. In a metallic casket, the combination, with the cover D, the face of which is depressed step-like, as shown, to provide a frame for the face-glass at a point below the plane of the top or face of the cover, of the glass e, the metallic frame e', secured to the cover D on a line with the face of said cover, and the rubber or flexible gaskets interposed between the 25 rim and glass and between the glass and depressed portion of the cover D, said depressed portion having a face-glass opening, substantially as described.

2. In a casket, the combination, with the

cover D, having the depressed face, said depression being open at its center, and so shaped as to form shoulders d d' , the one d supporting a face-glass, and the one d' having a frame, e', bolted thereto to hold the glass in place, said glass and frame being below the level of 40 the face of the cover D, of the face-glass-protecting cap E, open at its center, and provided with a cover, E', secured thereto, all substantially as shown and described.

3. In a metallic casket, the body constructed 45 in four sections—i. e., two sides, A, and two ends, B—flanged internally and externally at their upper ends, flanged internally at their lower end, and secured together at their seam by the angle-plates H G, having bolts 50 extending through the internally-projecting flanges of the sides and ends, and constructed as shown, in combination with the cover D, having shouldered face-glass openings, and the face-glass frame e', with its glass secured 55 therein, said cover being adjustably secured to the body by the clips I, pivoted to the outwardly-projecting flange of the body, and having jaws to grasp the cover to hold it in place, all arranged and constructed substantially as 60 shown and described.

In witness whereof I have hereunto set my hand and seal at Springfield, Ohio, this 20th day of March, A. D. 1885.

DANIEL B. HISER. [L. s.]

In presence of—

P. J. CLEVENGER,
WILLIAM A. FRY.
